UNITED STATES PATENT OFFICE.

AUGUST VON BORRIES, OF HANOVER, GERMANY, ASSIGNOR TO HIMSELF,
THOMAS WILLIAM WORSDELL, OF STONYCROFT, ENGLAND, AND RICH-
ARD HERBERT LAPAGE.

COMPOUND ENGINE.

SPECIFICATION forming part of Letters Patent No. 511,581, dated December 26, 1893.

Application filed August 11, 1892. Serial No. 442,774. (No model.) Patented in Switzerland, 1892, No. 5,050, and in Germany February 27, 1893, No. 67,234.

To all whom it may concern:

Be it known that I, AUGUST VON BORRIES, a subject of the Emperor of Germany, residing at Hanover, in the Empire of Germany, have invented certain new and useful Improvements in Compound Engines, of which the following is a specification, and for which patents have been granted in the countries of Switzerland, No. 5,050, 1892, (provisional,) and 10 in Germany, No. 67,234, February 27, 1893.

This invention relates to valve apparatus for compound engines whereby an engine provided therewith can be worked at will either as a compound engine, or as a non-compound engine, as for instance when it is desired that the power of the engine should be temporarily increased to meet special demands above the normal working average, as for example, in the case of a locomotive, for ascending an incline, 20 for starting a heavy train, or for shunting rapidly. According thereto within a suitable valve case are arranged two connected piston valves that control passages between the receiver and the low pressure cylinder, between 25 the receiver and the low pressure exhaust passage and between a high pressure steam pipe and the low pressure cylinder. One of these valves, hereinafter called for distinction the exhaust valve, is larger than the other and 30 serves when the engine is working compound to prevent the passage of steam from the receiver to the low pressure exhaust passage direct. The smaller valve (hereinafter termed the steam valve) is under these circumstances 35 inoperative, but by admitting live steam behind it, both it and the exhaust valve will be automatically moved into such positions that the exhaust from the high pressure cylinder can pass from the receiver direct into the low 40 pressure exhaust pipe, while the said live steam will pass at a reduced pressure into the low pressure cylinder which thereby becomes for the time being, a high pressure cylinder, with a consequent augmentation of power in 45 the engine.

In the accompanying drawings, Figures 1 and 2 are longitudinal central sections of valve apparatus constructed according to this invention, Fig. 1 showing the valves in posi-

tion for working the engine to which they are 50 applied, compound, while Fig. 2 shows the valves in position for working the engine as a non-compound engine.

A is a valve case formed with a high pressure exhaust passage B B' adapted to form 55 part of the connecting pipe or receiver between the high and the low pressure cylinders, and with another passage C C' adapted to form part of the low pressure exhaust pipe or passage.

D is a valve, herein called the exhaust valve; it is in the form of a piston and is arranged to control an exhaust port or passage E connecting the two passages B B' and C C' and to control the flow of exhaust steam through 65 the passage B B' from the high to the low pressure cylinder.

F is a valve, herein called the steam valve; it is in the form of a piston, and is arranged to work, as shown, in a cylindrical portion or 70 extension A' of the valve case provided with a steam inlet G that is in communication with the main steam pipe, or direct with the boiler, or is adapted to be placed in communication with either by a cock or valve that may be 75 worked by hand or from the reversing rod, or by a suitable construction of regulator valve as will be readily understood without drawings.

A² is an opening for placing the front end 80 of the extension A' in communication with the atmosphere, so that the valve F can make its outstroke easily.

The two valves are connected by a rod H. The steam valve F is arranged to control the 85 passage between the said inlet G for live steam and the valve chest of the low pressure cylinder or cylinders. In the arrangement shown the rod connecting the exhaust and steam valves D F is solid and made in two parts of 90 different diameter, the part H', of larger diameter being arranged to work through a partition or diaphragm A* placed between the cylinder in which the steam valve F works and the passage B B', and prevent live steam 95 flowing freely to the low pressure cylinder or cylinders until the exhaust valve D is fully opened as shown in Fig. 2 at which time the

part H^2 of the rod of smaller diameter will extend through the hole in the said partition or diaphragm and leave a free passage for live steam to the end B' of the said passage 5 B B' whence it can flow to the low pressure cylinder.

By the arrangement described when live steam is admitted through the said steam inlet G so as to act behind or upon the inner 10 end of the valve F , the two connected valves D F will be automatically moved by the pressure of the live steam on the steam valve F into the positions shown in Fig. 2. The exhaust valve D will then close the passage B B' between the high and low pressure cylinders and open the exhaust port or passage E , so that each cylinder can exhaust separately into the exhaust pipe or passage C C' , and the steam valve F will occupy a position 15 in which the part H^2 of the rod connecting the valve will extend through the hole in the partition or diaphragm A^* and leave an annular opening as shown that will effect a communication between the main steam 20 pipe or boiler and the valve chest of the low pressure cylinder or cylinders so that the engine will then work as an ordinary high pressure or non-compound engine. When the 25 supply of live steam to the steam inlet G is cut off, the valves will by reason of the greater 30 pressure on the exhaust valve of steam within that part B' of the receiver between the valve case and the steam chest of the low pressure cylinder, return automatically to their normal 35 positions shown in Fig. 1, and the engine will again work as a compound engine.

When the engine is working non-compound and the thicker part H' of the valve rod will have passed out of the hole in the intermediate 40 plate or partition A^* and formed a steam passage of such size as to reduce the pressure of the live steam that is then flowing through this hole (by throttling it), in such manner that the total force of the full pressure on the 45 smaller valve F is kept equal to the total force of the reduced pressure on the larger valve D . As a consequence of this arrangement the following important results are attained: If the 50 consumption of steam at the reduced pressure in the low pressure cylinder becomes greater, the pressure in the passage B' will be reduced a little thereby causing less force on the larger piston and motion of both pistons to enlarge the opening H^2 through plate till 55 the right amount of reduction is again reached. If the consumption of lower pressure steam is reduced, the pressure in B' will increase a little thereby causing the pistons to move back a little and reduce the size of the opening H^2 till the right reduction is again reached.

The amount of reduction is proportionate to the areas of piston valves F and D . Thus if the smaller one is one half the area of the large one the pressure in B' will be reduced 65 to one half. Furthermore this arrangement possesses the excellent feature of reducing the steam pressure in B' to the proper amount

to enable the total pressure on each piston to be equal when working non-compound thereby preventing too great a strain on the working parts and enabling the adhesion of the driving wheels of a locomotive to be utilized in the most advantageous manner. 70

What I claim is--

1. In a compound engine, the combination 75 with valves for controlling the communication between the high and low pressure cylinders, a high pressure exhaust port and a steam passage by which live steam can flow at a reduced pressure to the steam chest of the low pressure cylinder, of a steam chamber arranged to be directly connected with the main steam supply, and a steam actuated piston arranged to work in said cylinder and connected with said valves so as to actuate the 80 same in an automatic manner when live steam is admitted to said steam chamber substantially as herein described for the purposes specified.

2. In a compound engine, valve apparatus 85 for changing from compound working to non-compound working comprising a valve case having a steam passage adapted to form part of the pipe or receiver that connects the high and low pressure cylinders, a high pressure 90 exhaust port leading from said passage, a live steam chamber, and a steam reducing passage by which live steam can pass at a reduced pressure from said live steam chamber to the low pressure cylinder, valves adapted 95 to simultaneously control said main steam passage, high pressure exhaust port and steam reducing passage, and a steam operated piston arranged in said steam chamber and connected to said valves so that when steam is 100 admitted to said chamber it will automatically move said piston and connected valves into positions to open the steam reducing passage and high pressure exhaust port and close the steam passage between the high and low 105 pressure cylinders substantially as herein described for the purpose specified.

3. In a compound engine, a connecting passage between the high and low pressure cylinders, a low pressure exhaust passage, a high 110 pressure exhaust port, an exhaust valve adapted to simultaneously control said connecting passage and exhaust port, a passage for admitting live or boiler steam at reduced pressure to said connecting passage on the low 115 pressure side of said exhaust valve, and a steam valve subject to the pressure of live or boiler steam and adapted to control said last mentioned passage, said valves being of unequal area and connected together so as to 120 work simultaneously and automatically when the pressure upon one side of said steam valve is made greater than upon the other side substantially as described.

4. In a compound engine, a connecting passage 125 between the high and low pressure cylinders, a piston valve adapted to open and close said passage, an inlet for live steam, a contracted passage through which said steam

can pass to said connecting passage at the low pressure side of said valve, and a steam valve of smaller area than said piston valve and subject to the pressure of said live steam, 5 said valves being arranged at opposite sides of said contracted passage and connected by a rod adapted to control the passage of live steam at a reduced pressure through said contracted passage to the lower pressure cylinder substantially as herein described.

5. In a compound engine, a connecting passage between the high and low pressure cylinders, a piston exhaust valve adapted to open and close said passage, a chamber for live 15 steam, a piston steam valve adapted to work in said chamber and subject to the pressure of steam therein, a perforated plate arranged between said chamber and said connecting passage, and a rod connecting said valves and 20 extending through said plate, said valves being of unequal area and said rod being made of two diameters substantially as described for the purpose specified.

6. In a compound engine, a connecting passage B B' between the high and low pressure cylinders, a piston valve D adapted to control said passage, a chamber A' having an inlet at its inner end for live steam, and an opening at its outer end by which it is placed 25 in communication with the external atmosphere, a piston valve F arranged to work in said chamber and of smaller area than said piston valve D, a perforated plate arranged 30

between said chamber and said connecting passage, and a rod of different diameters connecting said valves and arranged to work through said perforated plate substantially as herein described for the purposes specified.

7. In valve apparatus for a compound engine, the combination of a valve case A having a connecting passage B B', a low pressure exhaust passage C C' and a high pressure exhaust port E between said passages, a cylindrical chamber A' having an inlet for admitting live steam to its inner end and an opening at its outer end by which it is placed in communication with the external atmosphere, a perforated plate arranged between said chamber and said connecting passage, a piston valve D arranged to control said connecting passage and said high pressure exhaust port, a piston valve F of smaller area than said valve D arranged to work in said chamber, and a rod of different diameters connecting said valves and arranged to work through said plate substantially as herein described for the purposes specified.

In testimony whereof I have signed my name to this specification in the presence of two subscribing witnesses.
